UNITED STATES PATENT OFFICE

EDWARD STANLEY, OF NORRISTOWN, PENNSYLVANIA.

PAPER-BAG MACHINE.

No. 830,259.

Specification of Letters Patent.

Patented Sept. 4, 1906.

Application filed October 28, 1903. Serial No. 178,868.

To all whom it may concern:

Be it known that I, EDWARD STANLEY, a citizen of the United States, residing at Norristown, in the county of Montgomery and State of Pennsylvania, have invented certain new and useful Improvements in Paper-Bag Machines, of which the following is a specification.

This invention relates to paper-bag-making machines, its object, as generally stated, being to provide a machine combining simplicity and durability of construction with ease and efficiency of operation, whereby the paper fed to the machine is first acted upon to produce a bag and whereby the completed bag is then folded into bellows form.

With this object in view the invention consists in the novel construction and combinations of parts, which will be hereinafter fully described and claimed.

In the drawings, Figure 1 is a side elevation of my improved bag-making machine. Fig. 2 is a sectional elevation thereof, showing the two main side frames and certain parts of the mechanism as seen at right angles to Fig. 1. Fig. 3 is a side elevation of the machine as seen from the side opposite to Fig. 1, certain parts of the machine being omitted. Fig. 4 is a plan view of the inclined extension-table, showing the mechanism mounted thereon. Fig. 5 is a vertical section through the creasing-rollers, as on the line 5 5 of Fig. 4. Fig. 6 is a transverse section, as on the line 6 6 of Fig. 4. Fig. 7 is a longitudinal section, as on the line 7 7 of Fig. 4. Fig. 8 is a sectional elevation of the first paste-box, as on the line 8 8 of Fig. 7. Fig. 9 is a sectional elevation of the carrying-belts for delivering the paper blanks to the formers, a portion of the former-carrying wheel, and adjuncts. Fig. 10 is a plan view of the second paste-box and adjuncts. Fig. 11 is a vertical section, as on the line 11 11 of Fig. 10. Fig. 12 is an elevation of the lower portion of the second paste-box and adjuncts, as seen at right angles to Fig. 11. Fig. 13 is a vertical section through the third paste-box, showing a portion of the series of formers and adjuncts. Fig. 14 is a plan view of the third paste-box, showing a development of the driving mechanism for the paste-rollers and adjuncts. Fig. 15 is a sectional development, as on the line 15 15 of Fig. 13. Fig. 16 is a sectional development, as on the line 16 16 of Fig. 9. Fig. 17 is an elevation of one of the formers, the radially-movable friction-roller

for removing the bag therefrom, and adjuncts. Fig. 18 is a sectional detail thereof, as on the line 18 18 of Fig. 17. Fig. 19 is an elevation of one of the friction-rollers, its arm, and slide-block. Fig. 20 is an elevation of a pair of folder-cams and their support, as seen from the line 20 20 of Fig. 15. Fig. 21 is a sectional detail thereof, as on the line 21 21 of Fig. 15. Fig. 22 is a similar view, as on the line 22 22 of Fig. 15. Fig. 23 is a sectional detail, as on the line 23 23 of Fig. 2, showing one of the supporting-arms for two of the folder-plates and the steam-passage therein. Fig. 24 is a sectional view of the hub of the former-carrying wheel and adjuncts. Fig. 25 is a sectional elevation of the mechanism for folding the bags and adjuncts. Fig. 26 is a sectional elevation of the mechanism for folding the bags, as seen at right angles to Fig. 25, and showing the moving parts in a slightly different position. Fig. 27 is a development in plan of the mechanism for folding the bags. Fig. 28 is a fragmentary detail of the belts for delivering the finished bags from the machine. Figs. 28 to 34, inclusive, are perspective views showing the successive operations through which a blank passes during the formation of a bag and during the subsequent folding thereof.

The framework of the machine, as generally stated, comprises the side frames 1 and 2, their tie-bars 3, the inclined extension 4, and the supporting-standard 9 therefor.

The main driving-shaft 10 is journaled in a bearing 12 on the side frame 2 and is provided with a suitable driving-pulley 13.

Journated in suitable bearings on the standard 9 is a shaft 14, on which is mounted a roll of paper 16 of sufficient width to form the four sides of a bag. The paper passes from the roll 16 over a guide-roller 17, between creasing-rollers 24 25, over the top of a table 26, over a pasting-roller 27, and between feed-rollers 28 29, by means of which it is drawn from the roll 16. The table 26 is supported by brackets 30 and 31 on the respective sides of the extension 4.

The upper creasing-roller 24 may be constructed of any suitable yielding material—such, for example, as rubber—and is mounted on a shaft 32, having its bearings in boxes 33 on the brackets 30 31. The lower creasing-roller 25 is mounted on a shaft 34, having its bearings in boxes 35 on the brackets 30 31, and is provided with disks 36, arranged in line with the travel of the paper and corre-

sponding in number and position with the folds to be produced in the sides of the bags. The disks 36 are slightly larger in diameter than the roller 25, to the end that as the paper is drawn between the rollers 28 29 the disks 36 will press the paper into the yielding surface of the roller 24, and thereby produce longitudinal creases in the strip of paper.

The lower feed-roller 29 is fixed to a shaft 37, which is journaled in the brackets 30 31, and the upper roller 28 may be constructed of yielding material and is mounted on a shaft 38, having its bearings in boxes 39 on the brackets 30 31. One end of the shaft 37 of the lower roller 29 extends outwardly and is provided with a gear-wheel 40, which is driven by an idler 41, coacting with a gear-wheel 42 on a shaft 43, hereinafter referred to. This shaft 43 is provided with a bevel gear-wheel 44, which is driven by a similar wheel 45 on one end of a shaft 46, journaled in bearings 47 and 48 on the extension 4 and side frame 2, respectively. The other end of the shaft 46 is provided with a bevel gear-wheel 49, in mesh with a similar wheel 50 on the main driving-shaft 10.

The paste-roller 27 is arranged in a paste-containing box 51, located at one side of the table 26, and the roller 27 is fixed to a shaft 52, which extends through and is journaled in the lower portion of said box. The wall of the paste-box 51 above the roller 27 is provided with an offset 53, through which one edge of the strip of paper passes, and the roller 27 projects through an opening in the offset 53 and slightly above the top line of the table 26, so as to apply a line of paste along the under side of one edge of the onwardly-moving strip of paper. One end of the shaft 52 projects outwardly and is provided with a gear-wheel 54, which is driven by a gear-wheel 55 on the shaft 37 of the lower feed-roller 29.

The paper is advanced from the feed-rollers 28 29 to and between a pair of rollers 56 and 57. The upper roller 56 is fixed to a transverse shaft 58, which is arranged parallel to the driven shaft 43, hereinbefore referred to, and the lower roller 57 is fixed to the shaft 43, both shafts being journaled in the brackets 30 and 31. The driven shaft 43 is provided with a gear-wheel 59, which meshes with a similarly-pitched gear-wheel 60 on the shaft 58, whereby the rollers 56 and 57 are driven at the same rate of speed. The upper roller 56 carries a longitudinally-arranged knife 61, which is adapted to register with a narrow opening 62 in the lower roller 57, and thereby sever the onwardly-moving strip of paper into predetermined lengths, each length of paper constituting a blank of sufficient size to form a paper bag. The knife 61 is provided with an offset 63, as shown, to the end that each blank of paper after it has been severed from the strip, as

just described, will be provided with an offset z in one end thereof and a projection x at the opposite end thereof, as shown in Fig. 28.

Before being acted upon by the knife 61 the forward end of the strip of paper extends to and between a pair of feed-rollers 64 and 65, mounted on shafts 66 and 67, respectively. The shaft 66 of the upper roller 64 is journaled in boxes 68 on brackets 69, rising from the extension 4, and the shaft 67 of the lower roller 65 is journaled in the brackets 69, and it is provided with a gear-wheel 70, which is driven by an idler 71, coacting with the gear-wheel 59 on the driven shaft 43. The roller 65 is provided with a groove 72, to which is fitted a carrying-belt 73, which passes over supporting-rollers 74 and around a pulley 75. The rollers 74 and the pulley 75 are journaled in a frame 76, which is mounted on a bracket 77, projecting upwardly from a transverse bar 78, secured to the extension 4, the frame 76 being held in place by a set-screw 79. Resting upon the belt 73, directly over the rollers 74 and pulley 75, is a pressure-belt 86, passing around rollers 80, 90 having their bearings in a frame 81, which is fitted between lateral guides 82 on the under side of a bridge-bar 83, supported by brackets 84, rising from the extension 4. The frame 81 is held against longitudinal movement by a suitable screw 85.

The surface speed of the roller 65 and belt 73 is greater than that of the feed-rollers 28 and 29, and the pressure of the roller 64 upon the roller 65 is such that the belt 73 and rollers 64 65 will slip upon the forward end of the paper until the blank is severed therefrom by the knife 61, whereupon the severed length of paper or blank is carried onward by the rollers 64 65 and belt 73 at a greater rate of speed than that of the onwardly-moving strip of paper. The blank passes between the belts 73 and 86, and the weight of the rollers 80, belt 86, and frame 81 press the blank upon the belt 73 in a manner to insure its passage therewith.

It will be observed that the top of the table 26 is provided with a groove 87 directly beneath the travel of the line of paste applied by the roller 27, that the rollers 28 29 and 64 65 and belts 73 86 do not extend to the lateral edges of the paper, and that the roller 57 is provided with a circumferential groove 87 directly beneath the line of paste. This construction insures the passage of the paper to and with the belts 73 86 without in any way affecting the line of paste applied by the wheel 27.

By the mechanism hereinafter described each successive blank is formed into a bag, and each bag is then folded to bring two opposite sides thereof close together and to bring the bottom of each bag adjacent and substantially parallel to said opposite sides, thereby producing a perfectly flat bellows- 130

folded bag that may be readily opened for use.

To produce the bag, the blank passes through the following operations, which, as generally stated, consist, first, in folding the blank into channel form, as indicated in Fig. 29; secondly, in folding the sides of the channel to meet each other and pasting the meeting edges together, and thereby forming a rectangular tube having the sides *a*, *b*, *c*, and *d*, as indicated in Fig. 30; thirdly, in applying paste to the inner face of the projection *x*; fourthly, in folding the sides *a* and *b* to meet each other at one end of the tube and pasting the projection *x* on the folded end of the side *b*, thereby forming the outwardly-projecting flaps *e* and *f*, as indicated in Fig. 31; fifthly, in applying paste to the inner faces of the flaps *e* and *f*, and, finally, in folding the flaps *e* and *f* toward each other and upon the folded ends of the sides *a* and *b*, thereby producing a bag, as indicated in Fig. 32.

I shall now proceed to describe the preferred mechanism for producing the paper bags, as follows: As the blanks are severed from the strip of paper by the knife 61 they are successively advanced and fed by the belts 73 86 to a moving series of formers 88, which are mounted on a suitable carrier. In the present instance the carrier comprises a wheel 89, fixed to a hub 90, which is rotatably mounted in a bracket 91, projecting from the side frame 2. The hub 90 is provided with a bevel gear-wheel 92, which coacts with a similar wheel 93 on the upper end of an inclined shaft 94, journaled in bearings on the side frame 2. The lower end of the shaft 94 is provided with a bevel gear-wheel 95, which is driven by a similar wheel 96 on a shaft 97, mounted in a bearing 98 on the side frame 2 and arranged adjacent to the main driving-shaft 10. The shaft 97 is driven by the shaft 10 through a pair of coacting gear-wheels 99 and 100, secured to the shafts 10 and 97, respectively, whereby through the gearing just described the wheel 89 is slowly rotated and the formers 88 brought successively into line with the blank-carrying belts 73 86.

Each former 88 in the present instance comprises a bracket 102, secured to the wheel 103, and a pair of radially-projecting parallel plates 104 and 105, around which the bags are formed. The plate 103 projects rigidly from the bracket 102, and the plate 104 is pivoted to the bracket 102, as at 105, so as to have a movement toward and from the plate 103, for a purpose hereinafter explained. A suitable spring 106, interposed between the plates 103 and 104, serves to maintain the plate 104 in the position shown in Fig. 13—that is, parallel to the plate 103. The plate 104 is provided on its outer end with an extension 107, arranged at right angles to the plates and forming in con-

junction with the outer end of the plate 103 the end of the former 88, against which the bottom of the bag is folded, the extension 107 being adapted to work in an offset 108 in the plate 103 when the plate 104 is moved on its pivot 105. The plate 104 projects inwardly from its pivot 105 and is provided on its inner end with a roller 109, which is adapted to act against a cam 110, and thereby move the plate 104 toward the plate 103 against the action of the spring 106. The cam 110 is mounted on the inner end of a sleeve 111, projecting fixedly from the side frame 1 and arranged in line with the hub 90 of the wheel 89. The hub 90 and sleeve 111 are made hollow for the reception of a shaft 112, by means of which they are held rigidly in alignment.

The feeding of the blanks is so timed in respect to the movement of the wheel 89 that as the upper surface of each successive former 88 in coming into line with the top of the belt 73 the latter delivers a blank between said former and a pair of parallel plates 113 114, supported by arms 115, projecting from the bridge-bar 83 toward the center of the wheel 89. The plates 113 114 are arranged on the respective sides of the path traversed by the formers 88, and the spaces between the inner faces of said plates and the respective sides of the formers 88 are each equal to the thickness of the paper, or substantially so.

Just as the rearward edge of the blank leaves the belt 73 the top of the former passes between the lower edges of the plates 113 114. This operation stops the forward movement of the blank and during the continued upward movement of the former folds the sides of the blank down against the respective sides of the former, the end of the blank which is to form the bottom of the bag projecting beyond the outer end of the former.

In order to bend each blank into channel form before it is engaged by the former 88 and folded between the sides thereof and the plates 113 114, I provide a pair of oppositely-disposed spiral cams 116 117, secured to the under side of the bridge-bar 83 and arranged in the path traversed by the sides of the blanks, as shown. These cams 116 117 engage and bend down the sides of the blanks as they are carried by the belts 73 86, so that each blank is bent, but not folded, into channel form before being introduced to the former 88, as indicated in Fig. 6.

As the former moves upwardly between the arms 115 and the plates 113 114 thereon the sides of the blank are held against the sides of the former 88 by frictional engagement with said plates, the respective sides of the blank extending below the bottom of the said former.

Arranged on the respective sides of each former 88 is a pair of oppositely-disposed

folder-plates 118 and 119, which are arranged to move toward and away from each other through a plane which is parallel and adjacent to the rearward side of the outwardly-moving former. These plates 118 and 119 are supported by arms 120 and 121, respectively, projecting from the wheel 89, the arms 120 projecting radially from the wheel 89 to support the plates 118 on one side of the formers 88 and the arms 121 projecting laterally beyond the formers and then radially to support the plates 119 on the opposite side of the formers. The plates 119 are adapted to slide upon brackets 122, projecting laterally from the arms 121, and are held in place and guided by undercut guide-plates 123, secured to said brackets, and the plates 118 are adapted to slide upon lateral extensions 124 of the arms 120 and are held in place and guided by undercut guide-plates 125, secured to said extensions similarly to the plates 119.

The plates 118, 119 are provided with rollers 126, 127, which project into spaces 128, 129 between the lateral edges of said plates, respectively. These rollers 126, 127 are adapted to act against fixed cams 130, 131 and 132, 133, respectively, during the rotation of the wheel 89 to move the plates 118, 119 to and from the formers 88 for a purpose hereinafter explained. The cams 130, 131 are supported by brackets 134, 135, projecting from the side frame 2, and the cams 132, 133 are supported by brackets 136, 137, projecting from the side frame 1.

Arranged at right angles to each of the plates 118, 119 is a folder-plate 138, which is adapted to move to and from the adjacent former 88 through a plane parallel and adjacent to the outer end of said former. These plates 138 are adapted to slide upon the outer faces of the arms 120 and are held in place and guided by undercut guide-plates 139, secured to the outer faces of said arms. The plates 138 are provided with rollers 140, which are adapted to act against fixed cams 141, 142 for a purpose hereinafter described. The cam 142 is supported by brackets 143, projecting from the side frame 2, and the cam 141 extends some distance around the path traversed by the rollers 140 and is supported by brackets 144, also projecting from the side frame 2.

The tops of the plates 113, 114 are provided with teeth 145, 146, respectively, and the inner ends of the plates 118, 119 are also provided with teeth 147, 148, respectively, the teeth 147, 148 being adapted to enter the spaces between the teeth 145, 146, respectively, during the rotation of the wheel 89 and the inward movement of the plates 118, 119.

As the bottom of each upwardly-moving former is passing the teeth 146 of the plate 114 the roller 127 engages the cam 133, which

moves the plate 119 inwardly, the teeth 148 of the plate 119 entering the spaces between the teeth 146 of the plate 114, and thereby folding the lower portion of the adjacent side of the blank up against the bottom of the former 88 before the said former escapes the teeth 146. After this side of the blank is folded as just described its edges extend beyond the center of the former 88, and the inner edge of the plate 119 is projected only a slight distance beyond the side of the former 88, thereby leaving the edge of the blank exposed. During the foregoing operation the plate 118 is being moved inwardly by its roller 126 engaging the cam 131, and immediately following the folding up of the lower portion of one side of the blank by the action of the plate 119 the teeth 147 of the plate 118 enter the spaces between the teeth 145 of the plate 113, and thereby fold the lower portion of the other side of the blank up against the former 88 and the exposed portion of the opposite edge of the blank, the paste previously applied to one edge of the blank by the roller 27 coming into contact with the opposite edge of the blank, and thereby uniting the respective edges. It will be observed that the inner edge of the plate 118 is projected beyond the center of the former 88 by the cam 131, thereby firmly holding the edges of the blank together and against the said former. The plates 118, 119 remain in engagement with the blank until the paste has dried sufficiently to hold the paper together, whereupon they are withdrawn, as will hereinafter appear. By holding the sides of the blank against the respective sides of the former 88 by the teeth 145, 146 until the teeth 147, 148 have folded the depending sides of the blank up against the bottom of the former I am enabled to fold the blank tightly around the former. At this stage of the operation the blank is formed into a rectangular tube having the four sides *a*, *b*, *c*, and *d*, as indicated in Fig. 30, the tube being around the plates 103 and 104 of one of the formers 88, with that portion of the tube which is to be folded into the bottom of the bag projecting beyond the outer end of the said former. It will be observed that the projection *x* of the blank is folded into the side *a* of the tube, thereby causing the side *a* to project slightly beyond the side *b* of the tube.

The next operation is to apply paste to the inner face of the projecting end *x* of the side *a* of the tube, and for this purpose I provide the following mechanism: 149 designates a bar extending between the side frames 1 and 2 and on which is slidably mounted an adjustable plate 150, which is held in place and guided by suitable undercut guide-plates 151. This plate 150 carries a paste-containing box 152, provided with an opening in one of its side walls, in which is arranged a paste-roller 130

153. One end of the roller 153 is provided with a gear-wheel 154, which coacts with a gear-wheel 155 on one end of a shaft 156, which has its bearings in a bracket 157 on the plate 150. The other end of the shaft 156 is provided with a bevel gear-wheel 158, which is driven by a similar wheel 159 on the lower end of an inclined shaft 160. The upper end of the shaft 160 is provided with a bevel gear-wheel 161, which coacts with a similar wheel 162 on a driven shaft 163, hereinafter referred to, whereby as the last-named shaft is actuated the roller 153 is rotated to keep a fresh supply of paste on its surface. The shaft 160 has its bearings in brackets 164 165, which are supported by the shafts 156 163, respectively. The shaft 156 is provided with a projecting arm 166, carrying on its outer end a paste-applying brush 167, which is arranged to engage and take paste from the roller 153 during the rotation of the shaft 156. As the brush 167 rotates with the shaft 156 it moves through the path traversed by the projection *x* on the outer end of the side *a* of the paper tube, and the rotation of the brush 167 is so timed in respect to the movement of the wheel 89 that as each former 88 passes the paste-box 152 the outer end of the brush 167 will engage and apply paste to the inner face of the projecting end *x* of the side *a* of the paper tube. The plate 150 is provided with a depending lug 168, which is engaged by the outer end of a screw 169, projecting from and screwed into the bar 149, and the gear-wheel 159 is secured to the shaft 160 by a set-screw 170, to the end that by loosening the set-screw 170 and manipulating the screw 169 the plate 150 may be adjusted toward or from the wheel 89 and the position of the paste-applying brush 167 thereby nicely regulated.

The blank is next acted upon by the outer curved end of a rotating folder-arm 171, which is arranged adjacent to the path traversed by the outer ends of the formers 88 and which projects from a collar 172, secured to a shaft 163, previously referred to. This shaft 163 is fitted to bearings 173 on a frame 174, extending between the side frames 1 and 2. The shaft 163 is provided with a bevel gear-wheel 175, which coacts with a similar wheel 176 on one end of a shaft 177, which is fitted to bearings on the side frame 2. The other end of the shaft 177 is provided with a bevel gear-wheel 178, which is driven by a similar wheel 179, secured to the hub 90 of the rotating wheel 89.

The folder-arm 171 moves in the direction indicated by the arrow in Fig. 13, and it moves at a greater rate of speed than that of the outer end of the former 88 to the end that as the former passes the folder-arm 171 the outer curved end of said arm will act upon the outwardly-projecting portion of the paper tube or blank in a manner to fold the

outer end of the side *b* of the tube up against the outer end of the former and under the outwardly-turned lower end of a fixed folder-plate 180, which extends upwardly along the path traversed by the outer end of the formers 88. During this operation the outwardly-turned end of the folder-plate 180 acts upon the outwardly-projecting end of the side *a* of the tube and folds the latter down upon the outer end of the former 88, the extension *x* of the side *a* overlapping the folded end of the side *b* and the paste previously applied to said extension uniting the meeting edges of the sides *a* and *b* together.

When the outer end of the tube or blank is being folded as above described, the corner-folds thereof are reversed and brought down to meet the lateral edges of the outer end of the former, thereby making oblique folds in the sides *c* and *d* and forming the flaps *e* and *f*, as shown in Fig. 31.

The sides *a* *b* of the blank just folded are held against the outer end of the former during the onward movement thereof by the folder-plate 180, the space between the outer end of the former and the folder-plate being of substantially the same thickness as the overlapping ends of the paper.

It will be observed on reference to Fig. 14 that the lower end of the folder-plate 180 is reduced in width and that the outer end of the folder-arm 171 is bifurcated to clear the reduced end of the plate.

The folder-plate 180 is secured near its lower end to a bracket 181, projecting from a bar 182, which extends between and is secured at its respective ends to the side frames 1 2.

During the onward movement of the wheel 89 and while the blank is passing the folder-plate 180 each outwardly-projecting flap *e* *f* passes between fixed plates 183 184, the plates 183 being mounted on the folder-plate 180 and the plates 184 being mounted on brackets 185, secured to the bar 182. This operation creases the oblique folds in the flaps *e* and *f*.

Mounted on the bar 182 and a bar 186, extending between the side frames 1 and 2, is a paste-containing box 187, in which are arranged paste-applying rollers 188 189, which project through openings in the respective sides of the box. These rollers 188 189 are fixed to the lower ends of shafts 190 191, respectively, which are mounted in bearings in the wall of the box. The upper ends of these shafts are provided with coacting gear-wheels 192 193, and the gear-wheel 192 is driven by a gear-wheel 194 on a shaft 195, which is journaled in a bearing 196 on the bar 182. The shaft 195 is provided with a bevel gear-wheel 197, which meshes with a similar wheel 198 on one end of a short shaft 199, mounted in a bearing on the bar 182. The other end of the shaft 199 is provided with a bevel gear-

wheel 200, which is driven by a similar wheel 201 on the upper end of a shaft 202, journaled in suitable bearings. The lower end of the shaft 202 is provided with a bevel gear-wheel 203, which meshes with a similar wheel 204 on the driven shaft 163, which carries the folder-arm 171.

The 187 paste-box is slightly narrower than the formers 88, and it is arranged between the fixed plates 184, which extend adjacent and parallel to the sides of the box.

Upon leaving the plates 183 the flaps *e* and *f* pass between the plates 184 and the paste-applying rollers 188 189, respectively, there-
15 by receiving paste on their opposing inner faces from the rollers 188 189, which project slightly beyond the outside line of the box 187, the plates 184 insuring the contact of the paper or flaps with the rollers.

20 Just as the outer end of the former 88 is escaping the end of the folder-plate 180 the outwardly-projecting flaps *e* and *f* are acted upon by two folder-cams 205 206, respectively, which are supported by brackets 207, projecting from the under side of the bar 186. These cams 205 206 comprise straight portions 208 209 and curved portions 210 211, respectively. The straight portions are arranged in line with the outer ends of the 25 formers 88 and between which the outer ends of the sides of the formers are adapted to pass, and the forward ends 212 213 of the curved portions 210 211 diverge outwardly from the path traversed by the outer ends of the 30 formers and gradually converge from their 35 diverging ends 212 213 to straight portions 214 215, respectively, which are arranged adjacent to the path traversed by the outer ends of the formers and are on a plane at 40 right angles to the straight portions 208 209, as shown in Figs. 13, 15, 20, 21, and 22.

As the former 88 passes the cams 205 206 the latter will act upon and fold the outwardly-projecting flaps *e* and *f* down upon the previously-folded ends of the sides *a* and *b*, the paste previously applied to the flaps *e* and *f* pasting said flaps to said previously-folded ends.

45 After the former 88 escapes the end of the folder-plate 180 the flaps *e* and *f* are held in engagement with the underlying folds by plates 216 and 217, respectively, extending fixedly from the bar 186 and along the path traversed by the outer end of the said former, 50 the plate 217 extending some distance beyond the plate 216.

As the former 88 is passing the plates 216 and 217 the plate 138 is being moved toward the former 88 by the roller 140 engaging the 55 cam 142 and the plate 138 is moved over and into engagement with the flap *e* just before the latter escapes the fixed plate 216, and the plate 138 continuing its movement moves over and engages the flap *f* just before the 65 last-named flap escapes the plate 217, there-

by holding the flaps at the end of the blank firmly together and against the outer end of the former 88.

The blank is now formed into a paper bag, as indicated in Fig. 32, around the former 88, 70 and the plates 118, 119, and 138 remain in engagement with the folds until the rollers 126, 127, and 140 meet the lower inclined ends 218, 219, and 220 of the cams 130, 132, and 141, respectively, or until the paste has dried 75 sufficiently to hold the folds together, whereupon the rollers 126, 127, and 140 engage the inclined ends 218, 219, and 220 of the cams 130, 132, and 141, respectively, and the plates 118, 119, and 138 are thereby withdrawn 80 from the former 88 for a succeeding operation.

I preferably heat the ends of the plates 118 and 138 which hold the folds of the paper together in order to assist in drying the paste, 85 and for this purpose I provide steam-passages 221, which extend through the arms 120 and their extensions 124 adjacent to the ends of the plates 118 and 138, as shown in Figs. 16 and 23. Each of these passages is connected 90 by a pipe 222 to a passage 223, extending through the hub 90 and opening into a space 224 between the end of the hub and a head 225, screwed onto said hub. The head 225 is provided with a stuffing-box 226, through 95 which a steam-pipe 227 extends. The steam is introduced to the space 224 through the pipe 227 and is distributed from the space 224 through the passages 223 and pipe 222 to the passage 221 in the arms 120.

Immediately following the withdrawal of the plates 118, 119, and 138 from the former 88 the bag is moved radially to project the bottom thereof a slight distance beyond the outer end of the former 88. The preferred 105 means to this end is as follows: Mounted on the wheel 89, adjacent to each former 88, is a radially-movable slide-plate 228, which is held in place and guided by a plate 229, secured to the bracket 102, and a suitable undercut plate 230, secured to the wheel 89. The inner end of the plate 228 is provided with a roller 231, which engages a fixed cam 232, by means of which the plate 228 is moved in and out when the wheel 89 is rotated, the roller 231 being held in engagement with the cam 232 by the action of a spring 233, secured at one end to the plate 228 and at the other end to a pin projecting from the wheel 89 through a slot 234 in the plate 228. The cam is mounted on a fixed shaft 112, projecting from within the hub 90 and into the sleeve 111, and is secured in place by means of screws 235, passing through the adjacent cam 110.

115 The plate 228 is provided with a pivoted arm 236, which carries a stud 237, on which is journaled a sleeve 238, carrying a friction-roller 239, preferably of rubber, which is adapted to bear against the former 88 under 120 125 130

the stress of a spring 240, projecting from the inner end of the arm 236 and bearing against a pin 241 on the plate 228. The sleeve 238 is provided with a ratchet-wheel 242, which is engaged by a spring-pawl 243, whereby as the slide-plate 228 is moving inward the roller 239 will be permitted to roll upon the former 88 and when the slide-plate 228 is moving outward the pawl 243 will engage the ratchet 242 and prevent the rotation of the roller 239. The arm 236 is provided with a beveled projection 244 to the end that as the slide-plate 228 is moving inward the projection 244 will engage a projection 245 on the plate 229 and just before the plate 228 reaches the limit of its inward movement move the roller 239 from engagement with the former 88. The slide-plate 228 remains in its innermost position while the bag is being made around the former, and after the plates 118, 119, and 138 are withdrawn from engagement with the bag the roller 231 engages the high part of the cam 232, thereby moving the slide-plate 228 outwardly. As the plate 228 is moved outwardly the projection 244 of the arm 236 escapes the projection 245 of the bracket 102 and permits the spring 240 to rock the arm 236 to engage the friction-roller 239 with the bag, and as the plate 228 continues its outward movement the roller 239, being held against rotation by the pawl 243 and ratchet 242, moves the bag to project the bottom thereof a slight distance beyond the outer end of the former 88.

After the bag has been moved radially, as just described, the former 88 meets one pair of arms 246 of a pair of rotating wheels 247, arranged side by side and fixed to a shaft 248, which is journaled in suitable bearings on the side frames 1 and 2. The shaft 248 is provided with a gear-wheel 249 which meshes with a gear-wheel 250 on the main driving-shaft 10, whereby the wheels 247 are rotated in synchronism with the wheel 89, thereby bringing the arms 246 to meet the former 88 successively.

The outer ends of each pair of arms 246 are provided with a pair of brackets 251, which extend toward each other and terminate before meeting each other to clear a centrally-arranged cam 252, hereinafter referred to. The inner ends of the brackets 251 are provided with plates 253, which afford a seat for the reception of the bottom of the bag. The brackets 251 are provided with oppositely-disposed reciprocal plates 254, which are held in place and guided by suitable undercut plates 255, so as to be movable toward and from each other.

The inner ends of the plates 254 are offset and provided with shafts 256, on which are mounted rocking collars 257, from which project oppositely-disposed folder-plates 258, which are moved inwardly toward each other

and outwardly away from each other when the collars 257 are rocked. Each folder-plate 258 is held normally outward by the action of a suitable spring 259, secured at one end to a pin on the collar 257 and at the other end to a pin 260, projecting from the bracket 251 and through a slot 261 in the slide-plate 254. The springs 259 also tend to move the slide-plates 254 normally outward. The end of the slots 261, engaging the pins 260, limits the outward movement of the plates 254. Depending from the collar 257 are arms 262, which enter openings 263 in the brackets 251 below the collars 257. These arms take against the inner ends of the openings 263 and as the slide-plates 254 are reciprocated control the movements of the folder-plates 258—that is to say, the springs 259, acting upon the collars 257, maintain the arms 262 in engagement with the inner ends of the openings 263, in consequence of which the in-and-out movements of the slide-plates 254 will rock the collars 257 on their shafts 256, and thereby rock the folder-plates 258 inwardly to a position substantially parallel and adjacent to the plates 253 and outwardly away from the plates 253.

The outer ends of the plates 254 are provided with rollers 264, which are adapted when the wheels 247 are rotated to engage fixed cams 265, and thereby move the plates toward and from each other, the springs 259 insuring the engagement of the rollers 264 with the cam 265.

The cams 265 are supported on the upper ends of arms 266, which are loosely mounted on the shaft 248, the lower ends of the arms being provided with bolts 267, which extend through slots 268 in brackets 269, secured to the floor, and thereby hold the arms 266 and cams 265 in position. By loosening the nuts on the ends of the bolts 267 the arms 266 and cams 265 may be nicely adjusted.

Pivoted to the inner ends of the brackets 251, as at 270, are the forward ends of rearwardly-extending arms 271, the free ends of the arms 271 being provided with rollers 272, which are adapted during the rotation of the wheels 247 to act upon the centrally-arranged cam 252, hereinbefore referred to, and thereby rock the arms 271 in unison on their pivots 270. The cam 252 is supported on the upper end of an arm 273, which is loosely mounted on the shaft 248 and provided on its lower end with a downwardly-extending thin plate 274. This plate is provided with a bolt 275, which extends through a slot in a bracket 276, secured to the floor, and thereby holds the arm 273 and cam 252 in position. By loosening the nut on the end of the bolt 276 the arm 273 and cam 252 may be nicely adjusted, similarly to the arms 266 and cams 265.

The rollers 272 of the arms 271 are held in engagement with the cam 252, and the arms

271 are rocked normally inward—that is, toward the center of the wheels 247—by the action of springs 277, secured at their respective ends to pins 278 and 279 on the arms 271 and brackets 251, respectively.

5 Projecting forwardly from the arms 271 are folder-plates 280, arranged to be rocked adjacent to the bag-receiving plates 253 and at right angles to the folder-plates 258. 10 These folder-plates 280 and likewise the pivot-points 270 of the arms 271 are in line with each other and constitute, in effect, a single plate and a single pivot, the only object in employing two arms 271 and two 15 plates 280 being to clear the plate 274 for holding the cam 252 in place.

As the arms 246 of the wheel 247 pass the cam 252 the rollers 272 engage said cam and rock the arms 271 to bring the folder-plates 20 280 down adjacent and substantially parallel to the bag-receiving plates 253. As the arms 271 near the end of the cam 252 the rollers 272 roll down the incline of the cam, and thereby permit the springs 277 to gradually lower the arms 271 to move the folder-plates 280 away from the plates 253.

25 As each pair of arms 246 of the wheels 247 are coming into line with a former 88 the roller 109 engages the cam 110 and moves the plate 104 toward the plate 103, thereby 30 loosening the bag upon the former 88, and the roller 231 engages the high part of the cam 232 and moves the slide-plate 228 outwardly, thereby causing the friction-roller 35 239 to engage and move the bag radially toward one pair of arms 246. Just as the arms 246 meet the former 88 the bottom of the bag reaches the bag-receiving plates 253. At 40 this point the rollers 264 engage the cams 265, and during the continued movement of the wheels 247 the rollers 264, engaging the cams 265, gradually move the slide-plates 254 toward the plates 253. The triangular folder-plates 258 engage the bag and fold the 45 lower portions of the sides *c* and *d* inwardly upon the bottom of the bag, and at the same time the folder-plates 280 engage the bag and fold the lower portion of the side *b* thereof inwardly upon the sides *c* and *d* being folded 50 and upon the bottom of the bag. A suitable plate 281 is provided to prevent the bag from moving forward upon the plates 253 while being acted upon by the folder-plates 280.

55 During the foregoing operation the bag is being withdrawn from the former 88, the sides *c* and *d* are drawn inwardly between the sides *a* and *b* and folded into bellows form, and the upper portion of the side *b* is folded down upon the lower portion thereof, as indicated in Figs. 9, 25, 26, 33, and 34, the sides *a* and *b* and the bottom of the bag being brought adjacent and substantially parallel to each other.

After the rollers 264 and 272 pass the high

parts of the cams 265 and 252, respectively, 65 the folder-plates 258 and 280 gradually move outwardly away from the plates 253. At this point the arms 246 meet the upper end of a driven inclined belt 282, under which the bag passes, and the outward movement of the plates 280 presses the bag into engagement with the under side of the belt 282 and tilts the forward end of the bottom of the bag outwardly to clear the stop-plate 281, as shown in Fig. 25. The surface of the belt 70 282 moves faster than the arm 246, and the frictional engagement of the belt 282 with the bag carries the latter forward to clear the folder-plates 280 of the folded end of the side *b* and permit the plates 280 to move onwardly without disturbing the folded bag.

75 Immediately following the starting of the bag with the belt 282 the forward end of the bag passes over the upper end of a narrow centrally-arranged inclined belt 283, between 80 which and the belt 282 the bag is carried onwardly from the arm 246.

85 The lower ends of the belt 282 and 283 pass around a pair of parallel rollers 284 and 285, respectively, the belt 283 being fitted to a groove in the roller 285, so as to lie flush with the latter. The upper ends of the belts 282 and 283 pass around rollers 286 and 287, respectively. The rollers 284, 285, 286, and 287 are mounted on shafts 288, 289, 290, and 90 291, respectively, the shafts 289, 290, and 291 being journaled in brackets 292, rising from a bar 293, which extends between and is secured to the side frames 1 and 2. The shaft 288 is journaled in boxes 297, which are slidably 95 fitted to openings in the brackets 292. Bearing upon the boxes 297 are suitable screws 298, by means of which the roller 284 may be pressed toward the roller 285. One end of the shaft 289 extends outwardly and is 100 provided with a pulley 294, which is driven by a belt 295, passing around the pulley 294 and a pulley 296 on the main driving-shaft 10, whereby the belt 283 is driven. The belt 282 105 is driven by frictional engagement with the 110 roller 285.

115 The bags as they are carried from the arms 246 by the belts 282 and 283 pass between the rollers 284 and 285, which crease the previously-folded sides of the bags and discharge 120 them from the machine.

125 An important feature of my invention is the employment of the rotating carrying-wheels for the blank during its formation into a bag and for the bag while it is being folded into bellows form. By this construction I am enabled to run a machine of the character described at a much higher rate of speed than has been heretofore attained, and consequently increase the output of the machine.

I wish it to be understood that I do not limit myself to the particular mechanism herein shown and described for effecting the

various operations, as the same may be greatly modified without departing from my invention.

I claim—

- 5 1. In a bag-machine, the combination of a mandrel means for folding a sheet of paper around the same to produce a tube, means for closing one end of the tube to produce a bag and means for moving the bag from the mandrel and for bellowsing the same, the last-named means including a movable carrier for advancing the bag.
- 15 2. In a bag-machine and in combination, two carriers, means for moving the same in synchronism, means associated with one of the carriers for receiving a blank of paper, folding the same into a tube and closing one end of the latter to produce a bag, and means associated with the other carrier for taking the bag from the first carrier and bellowsing the bag, substantially as described.
- 25 3. In a bag-machine and in combination, two carriers movable in opposite directions, means for moving the same in synchronism, means associated with one of the carriers for receiving a blank of paper, folding the same into a tube and closing one end of the latter to produce a bag, and means associated with the other carrier for engaging the bag while on the first carrier, giving the same an initial bellows shape; and thereafter giving the bag a final shape, substantially as described.
- 35 4. In a bag-machine and in combination, two carriers, means for moving the same in opposite directions, means for moving the same in synchronism, means associated with one of the carriers for receiving a blank of paper, folding the same into a tube and closing one end of the latter to produce a bag, and means associated with the other carrier for engaging the bag while on the first carrier, giving the same an initial bellows shape, and then giving the bag a final shape after the same is entirely removed from the first carrier, substantially as described.
- 45 5. In a bag-machine and in combination, two rotating carriers, means for moving the same in synchronism, means associated with one of said carriers for receiving a blank of paper, folding the same into a tube and closing one end of the latter to provide a bag, and means associated with the other carrier for taking the bag from the first carrier and bellowsing the bag, substantially as described.
- 55 6. In a bag-machine and in combination, two rotating carriers, means for moving the same in synchronism, means associated with one of said carriers for receiving a blank of paper, folding the same into a tube and closing one end of the latter to provide a bag, and means associated with the other carrier for bellowsing the bag, said means including devices for giving the bag an initial shape acting upon the closed end of the bag while on

the mandrel, and other devices for giving the bag a final shape when released from the first-mentioned device, substantially as described.

7. In a bag-machine and in combination, two rotating carriers, means for moving the same in synchronism, means associated with one of said carriers for receiving a blank of paper, folding the same into a tube and closing one end of the latter to provide a bag, and means associated with the other carrier for bellowsing the bag, said means including devices for giving the bag an initial shape acting upon the closed end of the bag while on the mandrel, and other devices for giving the bag a final shape acting upon the bag after the latter has been entirely drawn off the mandrel, substantially as described.

8. In a bag-forming machine, the combination of a carrying-wheel for receiving a bag-blank, means for folding said blank to produce a bag during its travel with said wheel a second carrying-wheel for receiving the finished bag, means carried by said second wheel for folding the finished bag, and means for rotating said carrying-wheels in synchronism, substantially as described.

9. In a bag-forming machine, the combination of a carrying-wheel for receiving a bag-blank, means for folding said blank to produce a bag during its travel with said wheel, a second carrying-wheel for receiving the finished bag, means carried by said second wheel for folding two opposite sides of the bag inwardly throughout the length of the bag to produce bellows folds during the travel of the bag with said second carrying-wheel, and means for rotating said carrying-wheels in synchronism, substantially as described.

10. In a bag-folding mechanism, the combination of means for supporting a rectangular paper bag, a carrier for receiving and advancing the bag, a pair of oppositely-disposed sliding plates moving with the carrier, a pair of oppositely-disposed folder-plates moving with the carrier and adapted to fold two opposite sides of the bag inwardly between the two remaining sides, operative connections between said sliding plates and folder-plates, operating-cams for said sliding plates, a folder-plate arranged to fold one of said two remaining sides, and means for operating the last-named plate, substantially as described.

11. In a bag-folding mechanism, the combination of means for supporting a rectangular paper bag, a carrier for receiving and advancing the bag, a pair of oppositely-disposed sliding plates moving with the carrier, a pair of oppositely-disposed folder-plates to fold two opposite sides of the bag inwardly between the two remaining sides, said plates being pivotally connected to the

sliding plates, arms rigidly connected to said folder-plates and arranged to engage the carrier, means for operating the sliding plates, a folder-plate arranged to fold one of said two remaining sides, and means for operating the last-named plate, substantially as described.

12. In a bag-folding mechanism, the combination of means for supporting a rectangular paper bag, a fixed cam, a carrier arranged on the respective sides of the cam and adapted to receive and advance the bag, means for folding two opposite sides of the bag inwardly between the two remaining sides, a folder-plate pivotally connected to said carrier, and an arm rigidly connected to said plate and adapted to engage said cam whereby during the movement of the carrier the plate is operated to fold one of said two remaining sides, substantially as described.

13. In bag-forming mechanism, the combination of a rectangular former, a carrier for supporting and advancing the same, means for introducing a sheet of paper to said former, a pair of folder-plates arranged on the respective sides of the path traversed by said former, whereby as said former passes between the plates the paper is folded around three sides of said former and the sides of the paper projected beyond the fourth side of said former, means carried by the carrier for folding the projecting sides of the paper to meet each other and thereby form a paper tube, and means for closing one end of the tube to produce a bag.

14. In bag-forming mechanism, the combination of a rectangular former, a carrier for supporting and advancing the same, means for introducing a sheet of paper to said former, a pair of folder-plates arranged on the respective sides of the path traversed by said former, whereby as said former passes between the plates the paper is folded around three sides of said former and the sides of the paper project beyond the fourth side of the former, a pair of folder-plates carried by the carrier and adapted to be moved across the fourth side of said former to fold the projecting sides of the paper to meet each other and thereby produce a paper tube, means for moving the last-named plates, and means for closing one end of the tube to produce a bag.

15. In bag-forming mechanism, the combination of a rectangular former, means for supporting and advancing the same, means for introducing a sheet of paper to said former, a pair of folder-plates arranged on the respective sides of the path traversed by said former, whereby as said former passes between the plates the paper is folded around three sides of said former and the sides of the paper projected beyond the fourth side of said former, a pair of oppositely-disposed folder-plates traveling with

said former and adapted to be moved across the fourth side of said former to fold the projecting sides of the paper to meet each other and thereby form a paper tube, means for supporting and guiding the last-named plates, fixed cams adapted to move the last-named plates toward each other and across the fourth side of said former, means on the last-named plates for engaging said cams, and means for closing one end of the tube to produce a bag.

16. In bag-forming mechanism, the combination of a rectangular former, means for supporting and advancing the same, means for introducing a sheet of paper to said former, a pair of folder-plates arranged on the respective sides of the path traversed by said former, whereby as said former passes between the plates the paper is folded around three sides of said former and the sides of the paper projected beyond the fourth side of said former, a pair of oppositely-disposed folder-plates traveling with said former and adapted to be moved across the fourth side of said former to fold the projecting sides of the paper to meet each other and thereby form a paper tube, means for supporting and guiding the plates, fixed cams adapted to move the last-named plates toward each other and across the fourth side of said former, fixed cams adapted to move the last-named plates away from said former, means on the last-named plates for engaging said cams, and means for closing one end of the tube to produce a bag.

17. In bag-forming mechanism, the combination of a rectangular former, means for supporting and advancing the same, means for introducing a sheet of paper to said former, a pair of folder-plates arranged on the respective sides of the path traversed by said former, whereby as said former passes between said plates the paper is folded around three sides of said former and the sides of the paper projected beyond the fourth side of said former, a pair of folder-plates traveling with said former and adapted to move across the fourth side of said former and at right angles to the first-named plates to fold the projecting sides of the paper to meet each other and thereby produce a paper tube, means for moving the second-named plates, teeth projecting from the first-named plates, teeth projecting from the second-named plates and adapted to enter the spaces between the teeth of the first-named plates, whereby the second-named plates are engaged with the paper before the first-named plates escape the former, and means for closing one end of the tube to produce a bag.

18. In bag-forming mechanism, the combination of a rectangular former, a plate located to one side of said former and adapted to hold paper against said former, means for moving said plate and former past each other,

a plate arranged to move at right angles to the first-named plate and adjacent to another side of said former to engage and fold the paper against said former, means for moving the second-named plate, teeth projecting from the first-named plate, and teeth projecting from the second-named plate and adapted to enter the spaces between the teeth of the first-named plate, whereby the second-named plate is engaged with the paper before the first-named plate escapes the said former.

19. In bag-forming mechanism, the combination of means for supporting and advancing a rectangular paper tube, means arranged in the path traversed by one end of the tube to fold said tube to close one of its open ends, means for applying paste to one or more of the folds previous to folding, means for holding the folds together while the paste is drying, and a spring-finger arranged to hold the folds together preceding the engagement of the last-named means with the folds.

20. In bag-forming mechanism, the combination of a former adapted to carry a paper tube having one of its ends projecting beyond one end of the said former, means for moving the former in a substantially circular path, means for folding the projecting end of the tube toward the adjacent end of the said former, means for applying paste to one or more of the folds previous to folding, a plate traveling with said former and having an additional movement in a direction substantially parallel to the axis of movement of the former for moving across the end of said former to engage and hold the folds in the end of the tube together while the paste is drying, means for supporting and guiding said plate, a fixed cam adapted to move said plate across the end of the said former, and means on said plate for engaging said cam.

21. In bag-forming mechanism, the combination of a former adapted to carry a paper tube having one of its ends projecting beyond one end of the said former, means for supporting and advancing said former, means for folding the projecting end of the tube toward the adjacent end of the said former, means for applying paste to one or more of the folds previous to folding, a plate traveling with the said former and adapted to be moved across the end of the latter to engage and hold the folds in the end of the tube together while the paste is drying, means for supporting and guiding said plate, a fixed cam adapted to move said plate across the end of the said former, a fixed cam adapted to move said plate from the end of the said former, and means on said plate for engaging said cams.

22. In bag-forming mechanism, the combination of a wheel means for supporting and rotating the same, a former carried by said wheel, means for introducing a sheet of paper to said former, means for applying paste to

the paper, means for folding said sheet around said former to produce a bag, means carried by said wheel for engaging a pasted portion of the bag, and means for heating the last-named means.

23. In bag-forming mechanism, the combination of a wheel, means for supporting and rotating the same, a former carried by said wheel, means for introducing a sheet of paper to said former, means for applying paste to the paper, means carried by said wheel for folding a sheet of paper around said former to produce a bag, said last named means including a folder-plate, means for projecting said plate over a pasted portion of the bag, and means for heating said plate.

24. In bag-forming mechanism, the combination of a wheel, means for supporting and rotating the same, a former carried by said wheel, means for introducing a sheet of paper to said former, means for applying paste to the paper, means for folding said sheet of paper around said former to produce a bag, a plate carried by said wheel, means for projecting said plate over a pasted portion of the bag, and means for heating said plate.

25. In bag-forming mechanism, the combination of a wheel, means for supporting and rotating the same, a former carried by said wheel, means for introducing a sheet of paper to said former, means for applying paste to the paper, means for folding said sheet of paper around said former to produce a bag, a plate carried by said wheel, means for projecting said plate over a pasted portion of the bag, a steam-passage arranged adjacent to said plate, and means for introducing steam to said passage.

26. In bag-forming mechanism, the combination of a wheel, means for supporting and rotating the same, a former carried by said wheel, means for introducing a sheet of paper to said former, means for applying paste to the paper, means carried by said wheel for folding said sheet of paper around said former to produce a bag, said last-named means including a folder-plate, means for projecting said plate over a pasted portion of the bag, a steam-passage arranged adjacent to said plate, and means for introducing steam to said passage.

27. The combination of a former, means for folding a sheet of paper around the same to produce a bag, a reciprocative slide arranged adjacent to said former, means for supporting and guiding said slide, means for reciprocating said slide, a friction-roller carried by said slide, means for engaging said roller with the bag, and means to prevent the rotation of said roller when engaged with the bag, whereby the latter is moved from said former as the slide is moved in one direction.

28. The combination of a former, means for folding a sheet of paper around the same

to produce a bag, a reciprocative slide arranged adjacent to said former, means for supporting and guiding said slide, a friction device carried by said slide, means for engaging said device with the bag, and means for reciprocating said slide, whereby as the slide moves in one direction the bag is moved from said former.

29. The combination of a former, means
10 for folding a sheet of paper around the same
to produce a bag, a reciprocative slide arranged adjacent to said former, means for reciprocating said slide, a friction-roller carried by said slide, means for engaging said
15 roller with the bag, a ratchet-wheel carried by said roller, and a pawl engaged with said ratchet-wheel to prevent the rotation of said roller during its engagement with the bag, whereby the bag is moved from said former
20 as the slide is moved in one direction.

30. The combination of a former, means for folding a sheet of paper around the same to produce a bag, a reciprocative slide arranged adjacent to said former, means for supporting and guiding said slide, means for reciprocating said slide, a friction device having a yielding connection with said slide and adapted to bear against said former, and means for moving said device away from said former as the slide nears the limit of its stroke 30 in one direction, whereby as the slide moves in the reverse direction said device will escape the last-named means and thereby engage and move the bag from said former.

In testimony whereof I affix my signature 35 in presence of two witnesses.

EDWARD STANLEY.
